ROCCO LAROSA, OF NEW YORK, N. Y.

COMBINATION LOCK.

Application filed July 30, 1925. Serial No. 47,106.

To all whom it may concern:

Be it known that I, Rocco LAROSA, a subject of the King of Italy, and a resident of the city of New York, borough of Manhattan, in the county and State of New York, have invented a new and Improved Combination Lock, of which the following is a full, clear, and exact description.

This invention pertains to locks and has particular relation to permutation or combination locks.

The invention primarily comprehends an improvement in permutation or combination locks, which renders the same more thoroughly efficient and effectual in operation, comparatively simple, but strong and durable in construction, and inexpensive to manufacture.

The invention furthermore contemplates a permutation lock in which means is provided for readily permitting the changing of the combination.

With the above recited and other objects in view, reference is had to the accompanying drawings in which there is exhibited one example or embodiment of the invention which is in no way intended as a limitation upon the scope of the appended claims as it is to be clearly understood that variations and modifications which properly fall within the scope of said claims may be resorted to when found expedient.

In the drawings—

Fig. 1 is a fragmentary sectional plan view taken approximately on the line 1—1 of Fig. 6;

Fig. 2 is a similar view taken approximately on the line 2—2 of Fig. 6;

Fig. 3 is an outer side view of the lock, with parts in section, as indicated on the line 3—3 of Fig. 2;

Fig. 4 is a vertical longitudinal sectional view taken approximately on the line 4—4 of Fig. 2, illustrating the locked condition of the lock;

Fig. 5 is a similar view illustrating the unlocked condition of the lock;

Fig. 6 is a longitudinal vertical sectional view taken approximately on the line 6—6 of Fig. 1;

Fig. 7 is a transverse section taken approximately on the line 7—7 of Fig. 6.

Referring to the drawings by characters of reference, 10 designates a door or other closure, and 11 the frame or jamb upon which the keeper 12 is mounted for receiving the projectible and retractile extremity 13 of a slidable bolt 14, which bolt is mounted for longitudinal sliding movement within the casing or housing 15. The opposite end 16 of the bolt extends at all times through the opposite end of the casing or housing 15 and is provided with a manipulating knob or handle 17. The casing or housing 15 is secured or attached to the inner side of the door 10 and the bolt is freely movable by the manipulating knob 17 at all times from within the door to engage or disengage the extremity 13 with the keeper throughout. The bolt is provided with a pair of longitudinal slots 18, through which the transverse guide stems 19 extend for guiding the bolt in its movement and for limiting the shifting of the same in opposite directions. The guide stems are carried by the outer side wall 20 and are provided at their opposite ends with axially threaded bars 21 to aline with openings in the inner side wall 22 of the casing. A detent 27 is also carried by a stud 25 and is engageable in the notches 28 in the upper edge of the bolt to hold the same in retracted, partially retracted, or fully projected position.

In order to provide means for actuating the bolt from the exterior of the door, a rotary manipulating shank 29 projects through the door a hollow bearing sleeve 30 secured to the outer side wall of the casing and into said casing. The shank 29 is provided with a reduced extremity 31, upon which a sleeve-like head 32 is keyed and retained against the shoulder 33 by a nut 34. The sleeve-like head is provided with a radial finger 35, which is adapted upon rotation of the shank in one direction, to successively engage the depending projections 36 and 37 to effect the projection and retraction of the extremity 13 of the bolt.

In order to provide permutation means for locking the shank against rotation so that the bolt may be locked in a projected locking position or a retracted unlocked condition, a longitudinally slidable locking plate 38 is provided, which is mounted on the

inner side of the outer side wall 20 of the casing, said plate being shiftable between the wall 20 and parallel guide lugs 39. The plate is further provided with slots 40 through which the guide stems 19 extend. The plate is provided with a laterally offset locking lug 41, which upon the shifting movement of the plate 38 in one direction, effects the engagement of the lug 41 within the keeper opening 42 of the sleeve-like head 32. A spring 43 is mounted on the stud 25 and engages a lug 44 on the locking plate for the purpose of normally shifting the locking plate in a direction to effect the disengagement of the locking lug 41 from the keeper opening 42. In order to lock the plate 38 against movement in a direction under the action of the spring 43 to effect the release of the locking lug 41 from the opening 42, the said plate is provided with a plurality of slots 45, each of which is provided at one end with a locking teat 46, one of which, designated by the reference character 46^a, is adapted to co-operate with the keeper opening 47 in a sleeve 48, which surrounds the shank 29. A portion of the sleeve 48 which extends beyond the outer side of the door and abuts against the manipulating knob 49 on the outer end of the shank 29, has keyed thereto a collar 50. The remaining teats 46 are adapted to engage within the peripheral keeper openings 51 in the rotary stems 52, which are arranged in parallel longitudinally spaced relation to each other and to the shank 29. The inner ends of the stems are journaled in bearing openings 53 in the inner wall 22 of the casing, with the outer ends 54 projecting beyond the outer ends of the bearing sleeves 55 which project inwardly from the outer side wall 20 of the casing. The said outer ends are provided with enlarged heads 56, between which heads and the outer ends of the bearing sleeves, collars 57 are arranged, the said collars 57 and the collar 50 being formed on their inner peripheries with a circumferentially spaced series of axial grooves 58 capable of selective engagement with a radial longitudinal key 59 on the projecting ends of the stems 52 or the sleeve 48. Each of the collars 57 is provided with circumferentially spaced indicia on its outer periphery and with a serrated portion 61 to facilitate turning thereof. The inner end of each stem 52 is provided with an axially threaded bore 63 for receiving a headed screw 64, which removably retains a washer 65 in a position to engage with the outer face of the inner side wall 22 to prevent outward axial movement of the stems 52. One of the keeper openings, designated 51^a, is of cam shape to engage with its teat 46 upon turning movement of the stem for the purpose of camming and shifting the locking plate 38 against the action of the spring 43 in a direction to cause all of the

teats 46 and 46^a to be disengaged from their keeper openings, while, at the same time, effecting locking engagement of the locking lug 41 in its keeper opening 42.

In order to provide means for covering and concealing the screws 64 and the nut 34, and to protect the same from dust or other foreign matter, a cover 66 is removably mounted on the outer side of the inner side wall 22, the same being maintained in place by a spring fastener element 67 engageable in a keeper opening 68.

In the operation of the lock, assuming the same to be unlocked so that the bolt is freely movable by manipulating the knob 49 on the outside of the door, to lock the door the knob is manipulated so that the bolt is shot to engage the extremity 13 in the keeper 12. In this position the keeper opening 42 in the sleeve-like head 32 of the rotary manipulating shank 29 is in the position illustrated in Fig. 5, whereby said keeper opening is in the path of movement of the locking lug 41. Either the locking sleeve 48 or the locking stems 55, or all of said stems and the sleeve, are turned by means of the collars 50 or 57, thereby disposing one or more of the keeper openings 47, 51 or 51^a, out of registry with the path of movement of the teats 46, so that the movement of the plate 38 under the action of the spring 43 is prevented, as illustrated in Figs. 2 and 4.

To release the rotary manipulating shank 29 to permit manipulation of the knob 49 to retract the bolt, the operator must turn the locking sleeve 48 and stems 52, so that the keeper opening 47, keeper opening 51^a and the remaining keeper openings 51 are disposed in registry with the path of movement of the teats 46. When all of said keeper openings are alined with the teats, the spring 43 will function to slide the plate in the direction indicated by the arrow in Fig. 4, so that the teats enter the keeper openings while the locking lug 41 is retracted or disengaged from the keeper opening 42, as illustrated in Fig. 5. The knob 49 and shank 29 are now freely rotatable to effect retraction of the bolt. When in this position, the locking operation is accomplished by turning the stem 52, which is provided with the cam notch 51^a, so that shifting of the plate 38 against the action of the spring is accomplished by the camming action of the notch 51^a against its teat 46. This throws the locking lug 41 into the keeper opening 42 and the remaining stems 52 and locking sleeve 48 may be turned for the purpose of confusing an uninitiated operator by disposing the keeper openings out of alinement with the teats.

When it is desired, the combination may be readily changed by removing the cover 66, whereby access is gained to the screws 54

and the nut 34. When the screws 64 are removed, the stems 52 may be drawn outwardly a sufficient distance to disengage the key 59 from the particular groove 58 in the 5 collar 57, and re-engage with a different groove, after which the screws and washers are re-assembled.

From the foregoing it will thus be seen that an improved, comparatively simple, and 10 inexpensive permutation lock has been devised.

What is claimed is:

1. In a permutation lock, a casing, a shift- 15 able bolt, a movable manipulating member engageable therewith for effecting shifting movement thereof and having a keeper opening, and a permutation mechanism for locking the member against movement and for releasing the same, comprising a locking 20 plate having a locking lug and normally shiftable in one direction to disengage the locking lug from the keeper opening in the manipulating member to disengage and unlock said manipulating member for 25 free movement, and a plurality of relatively adjustable devices engageable with the locking plate for preventing normal shifting movement thereof to a released position except when relatively adjusted with respect to 30 each other in a predetermined position.

2. In a permutation lock, a casing, a shift- 35 able bolt, a movable manipulating member engageable therewith for effecting shifting movement thereof and having a keeper opening, and a permutation mechanism for locking the member against movement and for releasing the same, comprising a locking 40 plate having a locking lug and normally shiftable in one direction to disengage the locking lug from the keeper opening in the manipulating member to disengage and unlock said manipulating member for free movement, and a plurality of relatively adjustable devices engageable with the locking 45 plate for preventing normal shifting movement thereof to a released position except when relatively adjusted with respect to each other in a predetermined position, said relatively adjustable devices comprising rotatory 50 elements having keeper openings, teats on the locking plate and exteriorly disposed manipulating means therefor having indicia inscribed thereon and indicating means on the casing with which said indicia are registerable 55 for determining the position of the keeper openings.

3. In a permutation lock, a casing, a longitudinally shiftable bolt mounted therein, manipulating means connected with the bolt 60 and disposed at the inner side of the casing to permit of the free projection of one end of the bolt from and a retraction of the same within the casing, a spring-pressed detent for holding the bolt from shifting to a 65 projected or retracted position, a rotary

manipulating shank having a keeper opening at its inner end and having its outer end projecting through the outer side of the casing, an exteriorly disposed manipulating knob on the outer end of the shank; inter- 70 engageable means on the inner end of the shank and on the bolt for effecting a shifting of the bolt upon rotation of the shank, and permutation means for locking the shank against rotation, consisting of a longitudinally shiftable locking plate within the casing having a locking lug engageable 75 within the keeper opening of the shank when shifted in one direction, a sleeve on the shank having a keeper opening at its inner 80 end and projecting through the outer side of the casing, a plurality of parallel longitudinally spaced stems extending through the outer side of the casing and each having a keeper opening in its inner end, a locking teat on the sliding plate for each of the keeper openings in the stem and sleeve, a spring for shifting the locking plate in a direction to disengage the locking lug from the keeper opening in the shank, whereby to 85 release the shank for retracting the bolt when all of the teats are in alignment with the keeper openings in the stems and sleeve, and indicia on the outer ends of the sleeve and stems for guiding an initiated operator 90 in setting the sleeve and stems to a position to release the lock.

4. In a permutation lock, a casing, a longitudinally shiftable bolt mounted therein, manipulating means connected with the bolt 100 and disposed at the inner side of the casing to permit of the free projection of one end of the bolt from and a retraction of the same within the casing, a spring-pressed detent for holding the bolt from shifting to 105 a projected or retracted position, a rotary manipulating shank having a keeper opening at its inner end and having its outer end projecting through the outer side of the casing, an exteriorly disposed manipulating 110 knob on the outer end of the shank, interengageable means on the inner end of the shank and on the bolt for effecting a shifting of the bolt upon rotation of the shank, and permutation means for locking the shank against rotation, consisting of a longitudinally shiftable locking plate within the casing having a locking lug engageable 115 within the keeper opening of the shank when shifted in one direction, a sleeve on the shank having a keeper opening at its inner end and projecting through the outer side of the casing, a plurality of parallel longitudinally spaced stems extending through the outer side of the casing and each having a keeper opening in its inner end, a locking teat on the sliding plate for each of the keeper openings in the stem and sleeve, a spring for shifting the locking plate 120 in a direction to disengage the locking lug 125

from the keeper opening in the shank, whereby to release the shank for retracting the bolt when all of the teats are in alignment with the keeper openings in the stems 5 and sleeve, and an indicia-bearing head on the outer ends of the sleeve and each stem having indicia thereon for guiding an ini-

tiated operator in setting the sleeve and stems in position to release the lock, and circumferentially adjustable means of connection between the heads and the stems and sleeve respectively, whereby to change the combination for releasing the lock. 10

ROCCO LAROSA.
